UNITED STATES PATENT OFFICE.

JACOB WILHELM ERBE, OF EISENACH, SAXONY, GERMANY.

COMBINED PIANO AND HARMONIUM.

SPECIFICATION forming part of Letters Patent No. 402,427, dated April 30, 1889.

Application filed September 28, 1888. Serial No. 286,680. (No model.) Patented in Germany February 18, 1888, No. 43,301.

To all whom it may concern:

Be it known that I, JACOB WILHELM ERBE, manufacturer, of Eisenach, in the Grand Duchy of Saxe-Weimar-Eisenach, in German Empire, have invented new and useful Improvements in Combined Piano and Harmonium, of which the following is a specification, reference being had therein to the accompanying drawings, no patents being obtained by me anywhere for this invention except in the German Empire by Letters Patent No. 43,301, February 18, 1888.

My invention relates to a piano combined with a harmonium, by means of which the piano alone or the harmonium, or both, may be played together by using one key-board only, and whereby the same uniform pressure is required to move the keys, whether the harmonium or the piano, or the two together, are being played.

This invention is illustrated in the accompanying drawings, in which—

Figure 1 is a longitudinal section of the combined piano and harmonium on the section-line C D of Fig. 2. Fig. 2 is a cross-section on section-line A B of Fig. 1. Fig. 3 is partly a section on line E F and a section on line G H of Fig. 2. Fig. 4 is a longitudinal section of the piano, showing a front view of the contrivance for displacing the decrescendo mechanism or leverage of the piano. Fig. 5 is a view, partly in section, of the floor or bottom of the key-board, showing also a side view of the decrescendo mechanism or leverage for reducing the compass or extent of the sound of the piano, or for entirely displacing the mechanism of the piano. Fig. 6 shows a horizontal section partly through the air-chamber at G H, Fig. 2, and partly through the wind-chest F, Figs. 1 and 2. Fig. 7 shows in cross-section the folding or movable and adjustable contrivance for the decrescendo mechanism or leverage. Fig. 8 is a plan of Fig. 7. Fig. 9 shows a cross-section of the mechanism of the register. Fig. 10 is a front view of this register mechanism, the wind-chest being cut through. Fig. 11 shows in section the arrangement of the register mechanism in the register producing "expressive" and "high play."

The combined piano and harmonium forms the union of the well-known instrument called

a "harmonium" with a piano in such a manner that the same key-board, in combination with suitable register mechanism, serves either 55 to play the piano alone or to play the harmonium and the piano together; lastly, to play the harmonium alone, the height or extent of sound of the instrument being increased or muffled or diminished by the arrangement 60 of a crescendo and decrescendo mechanism, or the piano being entirely thrown out of action. The harmonium can be further altered or modified in sound by different register mechanism, (bass, English horn, flute, clarinet, and such like.)

A characteristic feature of this combined piano and harmonium is that the keys can be constantly easily and uniformly played (it being a matter of absolute indifference as to 70 touch) whether the harmonium or the piano or both are played at the same time, and that in order to include or dispense with the harmonium nothing more is needed than to depress the bellows or to release them. In a 75 similar manner the motion of the decrescendo mechanism suffices to exclude or dispense with the use of the mechanism of the piano.

The mechanism of the piano may be of any desired construction with the exception of the 80 keys, which differ from the ordinary construction, inasmuch as they are lengthened at the rear and carry at their rear and lower sides valves f, by means of which are ordinarily covered or muffled the wind channels or passages 85 of the sound-boxes of harmoniums, and thereby the reeds being left free to vibrate when the said keys are raised.

The harmonium is arranged in the following manner: The bellows H for the wind are arranged in the front part of the case or chest of the piano and are moved up and down by the treadle a, with the intermediary of the lever a', having two arms, and of the connecting-rods a''. The wind taken up by the bellows in their up-and-down motion is driven through the vertical channels or passages b and through the lateral passages b' into the collecting-bellows G, which are formed upon a flooring, G', suspended at its four sides to 100 the floor G³ of the wind-chest by means of leather folds or bags G''. By means of springs L, which are arranged between the flooring G' and the top or part H' of the bellows H, the

collecting - bellows G are maintained constantly pressed together, while the wind supplied by the bellows H serves to expand the same. By this arrangement a proportionately-constant pressure of air is obtained in the collecting-bellows G. Above these latter bellows, G, is placed the wind-chest F, which is divided in two separate halves by a partition or division-wall, F', into which halves the air flows through two openings, c' c', controlled by the valves c c. These valves are set or actuated by the expressive and high-play register mechanism, hereinafter to be described.

From the wind-chest the wind enters the four sound-boxes E E through the openings d d', which are also capable of being closed or opened by the valves d² d³. These valves are moved by registers, and for this motion the bass, English-horn, flute, and clarinet registers are used. The sound-boxes form four separate spaces, which rest at d against the wind-chest F, with the aid of felt, and between which all communication is closed. The connection of these boxes with the wind-chest is rendered in this manner thoroughly airtight.

There are provided two vibrating reeds and two sound-boxes for each tone, so that the sound-power of the harmonium can be doubled. When the valves d² are opened, the wind enters rapidly in the front sound-box and only this front reed is sounded. When, on the other hand, the rear valve, d³, is also opened, the two reeds are simultaneously vibrated and the harmonium plays sharper or with more intensity. The reeds f' are placed at the lower part of the air-slots e e'. When the key g or g' is depressed for the purpose of playing, so that the rear part of the same is raised to a certain height, this key will, by means of its valve f, free the passage or channel for the reed f', and the wind, which is conducted either through one or through two sound-boxes E to the reed, allows the same to be sounded.

The registers which are made use of in this combined piano and harmonium operate upon the air-valves d² d³, which allow the wind to enter the front or rear sound-box as well as upon the expressive or high play, in order to allow the wind to proceed from the collecting-bellows to the wind-chest. The registers are arranged above the keys in the front board or wall of the piano, and are provided in a well-known manner with knobs or buttons upon which is inscribed the description of the corresponding register. The motion of the register is fully shown at a larger scale in Figs. 9 to 11.

The register-knob h, passing through the front ledge, h', of the piano, (see Figs. 9 to 11,) carries at the back a bolt, h², in which is formed an opening, h³, having the form of a slot. In this notch or slot is located one of the arms of the double-armed lever i, which is movable in the projecting wooden part of the sound-box E. The shorter arm, i', presses

against a plate, k, which is held by means of a small frame, l l, so as to be capable of turning around. While the lever-arm i' 70 presses from above downward against the plate k, the plate m² has a tendency to press the valve upwardly under the action of the spring m' and with the aid of the crank-lever m and of the draw-rod m³ of the valve. When the knob of the register is pulled out, the lever-arm i is moved in the direction of the arrow I, Fig. 9, and the arm i' of the crank-lever pushes the valve downwardly, whereby the pressure of the spring m' is overcome and 75 the corresponding valve is opened. With reference to these valves which are used for the rear sound-boxes, a similar cranked lever may likewise be employed. In this case the prolongation of the plate m² is pressed directly 80 against the prolongation m⁴ of the valve in valves which allow of the expressive and high play to be played and determine the entrance of wind in the wind-box F. In this manner the register is rendered capable of being easily drawn out and kept steadily in the position thus assumed. The registers are placed 85 in front and over the key-board, so as to be little disturbed while the instrument is being played, and yet to be easily accessible when 90 they have to be pulled out.

The piano, as already stated, may have mechanism of any suitable construction as well as pedals of the well-known or ordinary kind, and it is furnished with such an arrangement of parts that the said mechanism may be drawn back by means of a peculiar decrescendo device when the piano only is intended to be played, and the hammers can be brought in contact with the felt of an anvil 100 or counter-hammer, to be hereinafter described. This arrangement is clearly shown in Figs. 4, 5, and 6, while Figs. 7 and 8 show the arrangement of the decrescendo mechanism.

The mechanism of the piano is arranged in 105 a frame whose side walls, B, are arranged to move upon the bolt A' of the frame A A. Thus these side walls, and with them the mechanism of the piano, are rendered capable of being moved away from the rest of the frame. 110 It is to enable such removal to be accomplished that the decrescendo mechanism is used in the manner hereinafter described.

The mechanism is usually and constantly 115 pressed against the strings or chords by means of a spring, B², whose lower end is fixed to the frame A, while its upper extremity rests against the side wall, B. Too great a pressure of the mechanism is prevented by means of the slant projections or blocks B³, which are 120 arranged on the side walls of the frame A. In order to draw back the mechanism, the double lever o o' is made use of and fixed to the frame A in such a manner as to be able to turn freely thereon, while it is provided with 125 a cam-shaped boss, v', at the place where it passes, by means of its rod, through a slot, v², formed in the side walls, B. The short lever-arm o' carries an upright piece, counter-ham-

mer, or anvil, q , to which is fixed a bar, r , covered over with felt and serving as a brake to stop the hammers. When, now, the lever o is turned by means of the decrescendo mechanism in the direction of the arrow III, Fig. 5, the counter-hammer or anvil comes at once with its felt in front of the hammer, and in this manner muffles the sound. When, however, the lever-arm o is turned still farther from the right to the left hand side in consequence of the decrescendo mechanism being moved farther forward, then the cam-shaped boss v' is pushed against the front wall of the slot v^2 and moves the whole mechanism backwardly upon the bolt A' . The hammers are thus drawn so far back that they are in connection with the felted anvil or counter-hammer q , which, being at the same time moved higher up, prevents the hammer from striking the strings or chords. The decrescendo mechanism is let in the floor or bottom of the piano, and is moved by the knee of the player. In a slide-guide, F , Figs. 7 and 8, moves the sliding piece Q , which carries two small boards, $P P$, capable of being turned over or folded in a horizontal and in a vertical direction, whereby the rounded-off part w' , in conjunction with the spring w , prevents the unintentional turning of the small board P . These plates are shown close to one another in their expanded or unfolded state. A spring, x , bears with a certain amount of pressure against the sliding piece Q and prevents its moving automatically. The sliding piece Q is terminated at its rear end with a projection, R , carrying a rod, R' , screwed therein. In the space thus formed between the projection R and the rod R' is laid a lever, $p p'$, Figs. 4, 5, and 6, movable about a center or pin, p'' , and whose arm, directed outwardly, rests against the double lever $o o'$ of the decrescendo mechanism. The more the sliding piece Q is moved (to the right or left hand side) by the knee of the player the more the

lever $o o'$ will move in the direction of the arrow III and the less will the piano partake of the play, until at last it is entirely rendered mute and soundless. When it is therefore required to play the harmonium alone, nothing more is required than to push the decrescendo mechanism thoroughly to the right-hand side, while at the same time depressing the treadle a , which sets the bellows in motion. When, on the contrary, the piano only is required to be played, the decrescendo mechanism is left in its left-handed position and the treadles $a a$ are left alone or released, so that, the mechanism of the piano having been brought back, the playing takes place (with a silent keyboard as far as the harmonium is concerned) as generally effected by piano-players.

In order to increase the facility of operation of the various parts, hinges D^4 are arranged between the bottom part of the key-board C and the key-board ledge or support D , which ledge or support is firmly connected with the wood-work forming the rear part of the sound-boxes.

What I claim, and desire to secure by Letters Patent of the United States, is—

In a combined piano and harmonium, as hereinbefore described, the decrescendo mechanism consisting of the folding parts $P P$, sliding piece Q , lever $p p'$, acoustic hammer or anvil covered with felt, r , and a cam-shaped boss, v' , mounted in the frame B of the mechanism, substantially as described, for reducing the intensity of the tones of the piano or for entirely arresting the action of the hammers upon the string or chords and drawing back the frame of the mechanism, as set forth.

In witness whereof I have hereunto set my hand in presence of two witnesses.

JACOB WILHELM ERBE.
